UNITED STATES PATENT OFFICE.

CARL A. BRINK, OF ATTLEBOROUGH, MASSACHUSETTS, ASSIGNOR TO THE FRANK MOSSBERG COMPANY, OF SAME PLACE.

BICYCLE ALARM-BELL.

SPECIFICATION forming part of Letters Patent No. 641,827, dated January 23, 1900.

Application filed September 21, 1899. Serial No. 731,155. (No model.)

To all whom it may concern:

Be it known that I, CARL A. BRINK, of No. 28 South Main street, Attleborough, in the county of Bristol and State of Massachusetts, have invented certain new and useful Improvements in Bicycle Alarm-Bells; and I do hereby declare that the following is a full, clear, and exact description thereof, reference being had to the accompanying drawings, and to the letters of reference marked thereon, which form a part of this specification.

This invention relates to the alarm bells or gongs used on bicycles and like vehicles to give warning of their approach. It is fully explained and illustrated in this specification and the accompanying drawings.

Figure 1 represents the bell attached to a handle-bar of a bicycle as when in use. Fig. 2 shows the bell with one of the gongs removed to show the ringing mechanism inside. Fig. 3 is a section through the center of the bell in direction of line 3 3 in Fig. 2. Fig. 4 is a side view of the bell and ring-clasp by which it is attached to the handle-bar. Fig. 5 is an elevation of the stationary plate in the bell. Fig. 6 represents the moving plate and its operating-handle.

The objects of this invention are to simplify the construction of the bell, to lessen its cost, and make it less liable to get out of order and at the same time increase its efficiency as a reliable alarm to use on bicycles and other road conveyances.

The bell is made of two parts or gongs C C'. The part C has a hollow stud a, made fast to its center inside, and the hole in the center of the stud a has a screw-thread made in it to receive the screw c, which is made fast in the other gong C'. (See Fig. 3.) A three-pronged plate D (seen separately in Fig. 5) is rigidly secured to the end of the stud a at the hole o in the plate D. The upper end of the plate D is turned up at one side to form a loop v to form a double bearing for a small shaft h, which has a double hammer d made fast on one end and a crank g on the other end, by which the hammer d is operated. A movable plate J, which is shown in Fig. 6, is held on a stud n, fast in the stationary plate D, and has its lower end bent off to one side and carried through a notch r in one of the

gongs (see Figs. 2 and 3) to make a handle S to ring the bell by. The upper end of the movable plate J has a stiff open spiral spring f attached to it, and the upper end of the spring f is formed into a ring to receive the pin of the crank g in the upper end of the stationary plate D. A closed spiral spring H has one end attached to the outer end of the prong j of the stationary plate D and its other end hooked into the hole i in the movable plate J to draw back the plate J when it has been pushed-over to the dotted lines in Fig. 2.

The bell is attached to the handle-bar of a bicycle by means of a ring-clasp, one-half of which, k, is made fast to the back of the gong C and has one end turned out to form an ear e, and an opening m is made through the other end with a pin r on its outer edge. (See Fig. 3.) The other half of the clamp, k', has one end turned out to form an ear e', and a series of holes m' are made in the other end. The end k' is put through the opening m, and one of the holes m', is hooked onto the pin r, and a screw y, is put through a hole in one of the ears and screwed into the other ear to draw the two parts of the clamp together to clasp the handle-bar. By changing the pin r to another of the holes m' the size of the clamp can be made to fit larger or smaller handle-bars.

The bell is rung by pushing the handle S toward the left, as shown by dotted lines in Fig. 2. This motion of the plate J by the handle causes the upper end of that plate to throw the crank g over to the left by the spring f, and as soon as the crank passes the center the spring throws it up to the left quickly and causes the hammer d, as shown by the dotted lines in Fig. 2, to strike one of the gongs on that side, and when the pressure is removed from the handle S the spring H draws the plate J back, and as the crank again passes the center the spring f throws it up to the right again and causes the end of the hammer to strike the other gongs. This gives a stroke on each gong for every time the handle S is pushed over to one side. The hammer d is twisted out of its plane of motion, so that one end shall strike one gong and the other end shall strike the other gong. By

changing the spring H over to connect the other prong j' with the hole i' the action of the plate J will be reversed, so that the bell by a slight change can be used either on the 5 right or left hand handle-bar.

Having thus described my improvements, I claim as my invention and desire to secure by Letters Patent—

1. In an alarm-bell the combination of two 10 gongs, a stationary plate held on a stud fast in the center of said gongs, a short shaft having a hammer on one end and a crank on the other end held in bearings in the outer end of the stationary plate, substantially as de- 15 scribed.

2. In a bicycle-bell the combination of two 20 gongs held on one stud, a stationary plate held on said stud between said gongs, an oscillating lever pivoted to said stationary plate, a short shaft held in a bearing in the stationary plate and having a crank on one end and a hammer on the other end, a short spiral 25 spring connecting said crank on the end of the oscillating plate, substantially as described.

25 3. In a bicycle-bell the combination of a stationary plate, an oscillating plate pivoted to the stationary plate, a shaft held in a bearing on the stationary plate and having a ham-

mer on one end and a crank on the other end, a short stiff spiral spring rigidly secured to 30 one end of the oscillating plate and one end connected to the crank so the spring will be compressed as the crank passes the center and strike the gong by the expansion of the spring when the crank has passed the center, 35 and a closed spiral spring to connect said oscillating plate and stationary plate, substantially as described.

4. An adjustable clamp for bicycle-bells consisting of a U-shaped strip of metal fastened to the bell, one end being provided with a screw-threaded ear and the other end having an opening in it with a pin or buckle-tongue on the side nearest the end, an adjustable band passing through said opening and 40 having holes in it to fit on said pin or buckle-tongue, with a screw and a hole in the end of 45 said band to receive it, substantially as described.

In testimony whereof I have hereunto set 50 my hand this 18th day of September, A. D. 1899.

CARL A. BRINK.

In presence of—

PHILIP E. BRADY,

GEORGE A. MONROE, Jr.
